GRINDING MACHINE

Walter J. Wilson, Petersburg, Ind.

Application September 15, 1938, Serial No. 230,098

15 Claims. (Cl. 51—100)

This invention relates to grinding and shaping apparatus and pertains particularly to apparatus for grinding occlusal surfaces of posterior teeth. In the manufacture of dentures, extreme difficulty is experienced in producing a set of dentures because of the fact that there are not supplied by the manufacturers the proper materials of correct design which enables a dentist to make the dentures so that the occlusal surfaces of the teeth will come together in such a manner as to conform to the movements of the jaws, and it has been my conclusion that the dentist must start with the tooth design and manufacture the same so that the upper and lower occlusal surfaces of the teeth of a particular set will be matched and thus will conform to the motions of the jaws after they have been placed in a patient's mouth, thereby obtaining the correct action for the process of mastication and avoiding movement or tipping of the dentures such as commonly occurs in dentures constructed according to the present methods.

The present invention has for its primary object to provide an apparatus upon which may be cut models for upper and lower blocks of posterior teeth, accurately designed so that they will have interengaging or interlocking cusps which when cast in porcelain for mounting in dentures, will provide upper and lower posterior teeth which are accurately matched so as to conform to the motions of the jaws of the person wearing them.

Another object of the invention is to provide a grinding apparatus by means of which upper and lower posterior teeth may be produced having elliptic concave and convex surfaces of cusps formed on a curved outline which interlock, upper with lower, and permit an elliptic movement of the jaw, which is the natural movement which the jaw has during the process of mastication.

Still another object of the invention is to provide a grinding apparatus which is designed to facilitate the cutting of models for posterior teeth in which the cusps have elliptic concave and convex surfaces and having means whereby the porcelain tooth or block of teeth after being made from the model and fired, may be set back in the grinding apparatus in exactly the same position as that previously occupied by the model and have the curved cusp surfaces reground to the original form to overcome distortions produced in the porcelain through the firing process.

Still another object of the invention is to provide in a grinding apparatus of the character hereinafter set forth, a novel means for moving

a body along certain predetermined curved paths with respect to a grinding wheel whereby a desired grinding action is obtained.

A further object of the invention is to provide in a machine designed to facilitate the grinding of a body as above described, a means whereby the grinding operation may be carried out with respect to two bodies which are intended to work together, so that such bodies will have coacting cusps accurately matched to interlock for coacting grinding relation.

A further important object of the invention is to provide a tooth grinding apparatus by which may be produced upper and lower posterior teeth or blocks of such teeth having elliptic concave and convex surfaces of cusps on a curved outline which interlock and permit an elliptic movement of the jaw as may be readily demonstrated upon an articulator such, for example, as the articulator forming the subject-matter of my co-pending application filed of even date herewith, with the centers of the radii of all of the curves in the central median line plane, by which is meant an imaginary plane extending through the head and neck from the front to the back on the exact center dividing the body into two equal parts.

The invention will be best understood from a consideration of the following detailed description taken in connection with the accompanying drawings forming part of this specification, with the understanding, however, that the invention is not to be confined to any strict conformity with the showing of the drawings but may be changed or modified so long as such changes or modifications mark no material departure from the salient features of the invention as expressed in the appended claims.

In the drawings:

Fig. 1 is a view in front elevation of the grinding apparatus embodying the present invention.

Fig. 2 is a view in side elevation of the same.

Fig. 3 is a view in top plan of the apparatus.

Fig. 4 is a sectional view taken substantially on the line 4—4 of Fig. 3.

Fig. 5 is a view of one form of modeling block carrying frame.

Fig. 6 is a sectional view on the line 6—6 of Fig. 3.

Fig. 7 is a sectional view on the line 7—7 of Fig. 3.

Fig. 8 is a sectional view on the line 8—8 of Fig. 7.

Referring now more particularly to the draw-

55

ings, the numeral 1 generally designates a supporting base for the apparatus upon the top of which is formed, adjacent the edge which may be referred to as the rear edge of the base, the block 5 having a dove-tail slot 3 therein extending from front to rear. Upon the base block 2 is a carriage block 4 having upon its underface a dove-tail rib 5 slidably engaged in the slot 3. Upon the top of the carriage 4 is secured the vertical housing or standard 6 upon the upper end of which is a gear casing 7 through which extends a shaft 8. Within the casing 7 are suitable gears coupling the shaft 8 with a suitable driving shaft which is preferably of the flexible type and which is not shown but is carried upwardly through the standard 6 in a suitable manner to transmit power to the shaft 8. Upon one end of the shaft 8 is a grinding wheel or disk 9.

Suitable means is provided for constantly urging the grinding wheel forwardly with respect to a piece of work, such as a spring 10 coupled at one end with a pin 11 which is joined to the carriage 4 and at its other end to a stationary attaching means 12 secured to the base 1. In order that the operator of the apparatus may be able to shift the carriage 4 and the grinding wheel away from him and away from the work when necessary, there is provided the oscillatable lever 13 suitably pivotally supported intermediate its ends in the base block 2, as indicated at 14, and extending upwardly through a suitable recess in the carriage 4 to a point above the top of the carriage while its lower end extends below the base plate 1 and is provided with means, such as the eye 15, for the attachment of an actuating rod 16 thereto. The rod 16 is carried forwardly and has its other end connected with one end of a lever 17 which is pivotally supported upon the underside of the base by means of spaced ears 18 as shown.

The carriage 4 carries at its rear edge a bracket 19 having a threaded passage therethrough for the reception of an adjusting screw 20 which extends toward the front of the apparatus and 45 is designed to be shifted longitudinally thereof and the forward end of this screw is engaged by the upper end of the oscillatable lever 13. Thus it will be seen that when the operator of the apparatus oscillates the crank lever 17 to pull 50 the link bar 16 forwardly, the lever 13 will bear against the screw 20 and force the carriage rearwardly against the tension of the spring 10.

The forward movement of the carriage is limited by the rearwardly directed screw 21 which is 55 threaded through the passage in a bracket 22 mounted upon the base 1.

Upon the base 1 in front of the grinding wheel supporting carriage 4, there is formed the block 23 which is provided with a dove-tail slot 24 extending transversely of its top face or, in other words, extending across the base 1 perpendicular to the dove-tail slot 3 in which the carriage 4 slides. Upon the block 23 is a pivot post block 25 having a dove-tail rib 26 engaging in the dove-tail slot 24 and carrying the vertically extending tubular post 27 which terminates at its upper end in the horizontal circular plate 28. The hollow central portion 29 of the post 27 passes through the plate 28, as shown in Fig. 4, and receives a 70 pivot post 30, the upper end of which is formed integral with a disk 31 which rests upon and is concentric with the disk 28. An operating screw 32 is swivelly supported in a bracket 33 upon the base 1 and has threaded connection with the pivot post supporting plate 25, so that by means

of this screw, the plate 25 and the structure supported thereby may be moved transversely of the base 1 and consequently with respect to the grinding edge of the disk 9.

The forward edge of the non-rotatable disk 5 28 has set out thereon a scale 34 indicating degrees of a circle, starting at a zero point which lies in a vertical plane passing longitudinally through the apparatus or from the front to the rear thereof and through the thickness center of 10 the grinding wheel 9, and the upper or rotatable plate 31 has a suitable centering mark thereon, as indicated at 35 by which certain degrees of oscillation of the plate 31 and the structure which it carries, as hereinafter described, may be determined.

The rotatable plate 31 carries and preferably has formed integral therewith, a block or head-piece 36 which is provided in its top surface with a dove-tail slot 37 which extends longitudinally 20 of the apparatus perpendicular to the slot 24. This head-piece forming a part of the rotatable disk 31 is slidably coupled with the body 38 which is formed upon the underside of an elongated table bar 39 at the transverse center of the latter 25 and has a dove-tail rib 40 engaging in the slot 37. A bracket 41 carried by the rotatable disk or plate 31 supports an adjusting screw 42 which is engaged in a suitable threaded passage in the table bar block 38 and by this screw backward 30 and forward movement of the block and table is obtained.

At each end of the table 39 there is formed the depending sleeve 43 through which extends the lower end of a post 44, the post projecting a 35 substantial distance above the table bar 39 and passing through and having secured thereto a gear 45 which rests upon the table bar, as shown in Fig. 4. The lower end of the post may be held by any suitable means which will prevent upward movement of the post through the sleeve but permit the post to be freely rotated.

Lying upon the top surface of the table bar and extending longitudinally thereof is a rack bar 46, the teeth of which are in mesh with the 45 gears 45, as shown in Fig. 4, the rack bar being maintained in position with respect to the gears and held for sliding movement on the table bar 39, by suitable guides 47, which are secured to the table bar, as shown.

At a slight elevation above the table bar 39, each of the posts 44 is slightly reduced in diameter, as shown more distinctly in Fig. 7, to form a shoulder 48 and this upper reduced portion of each post is indicated by the numeral 49 and, as 55 shown in Fig. 8, is provided with four longitudinally extending slots 50 which are equi-distantly spaced around the post.

Secured in the slots 50 of each post are guide plates 51, 52, 53 and 54, the guide plates 51 and 52 60 having their vertical edges concave while the plates 53 and 54 have their vertical edges convex, and it will be noted that a plate 51 is spaced 180° from a plate 53 and that the machine when set up for use has a plate 51 of one post in edge opposed relation with a plate 53 of the opposite post. These plates are held in position in their respective slots by and between collars 55 encircling the reduced portion 49 at the upper and lower ends thereof and a nut 56 threaded upon 70 the upper end of each post and bearing against the upper collar.

The numeral 57 generally designates a hand unit which is used in connection with the other parts of the apparatus described. This hand unit con- 75

sists of a frame formed of a relatively long piece of bar material and shape to provide a central portion 58 connected with and offset from oppositely directed terminal portions 59 by the intermediate angular portions 60. The terminal portions of the frame are, through a portion of their length, of circular cross-section to form trunnions 61 upon each of which is a guide block 62 having a concave face 63 and a convex face 64. The curvature of these faces 63 and 64 correspond with the curvatures of the edges of the plates 53 and 51.

Inwardly of each of the blocks 62, the terminal portion 59 of the hand unit is provided with a suitable aperture to receive the eccentrically arranged threaded stud 63 extending from the end of a guide pin 64, the stud having a nut 65' threaded thereon to maintain the guide pin in position to extend rigidly from the terminal portion 59 to which it is attached, in a direction oppositely to the offset central portion 58 of the unit. This hand unit 57 is of a length whereby it will extend across the grinding apparatus from one post to the other, so that the blocks 62 may be positioned against the edges of certain of the plates carried by the posts and the distance between the remote sides of the pins 64 is such that these pins will engage the opposed edges of the inner ones of the guide plates as shown in Fig. 3.

The offset portion 58 of the hand unit has positioned against the inner side thereof one of two modeling block carrying frames, one of the frames being indicated generally by the numeral 65 while the other frame, shown in detail in Fig. 5, is indicated generally by the numeral 66. The frame 65, which is shown assembled with the hand unit, consists of a back bar 67 which is designed to position against the forward face of the offset portion 58, and a convex front bar 40 which is longitudinally slotted. The back bar carries the threaded stud 69 which extends through an opening 70 in the offset portion 58 to receive a clamping nut 71. By this means the frame 65 is held in adjusted position upon the hand unit.

The numeral 72 designates a shoe which is shaped upon one side to position against the convex face of the front bar 68 and the opposite face of this shoe is provided with a suitable means, such as the channel 73, for holding a modeling block such as is indicated by the numeral 74 in Fig. 4.

Extending from the rear side of the shoe 72 is a threaded stud 75 which passes through the slot of the front bar 68 and has threaded thereon the securing screw 76.

One side of the shoe 72 carries an index tooth 77 which is designed for engagement with the notches formed along the edge of an index bar 78 which is secured to one side of the bar 68, as shown in Fig. 3.

The frame 65 is employed during the modeling of an upper block of posterior teeth. For the modeling of a lower block, the frame 66 is used and this frame, like the frame 65, has a back bar 79 and a front bar 80, which is longitudinally slotted but the front bar is of concave form and the shoe 81, which is secured to the concave face thereof, has a convex back surface to conform to the concave form of the bar 80 against which it is held by the nut 82 which is threaded upon the stud 83 which passes through the slot of the bar 80 from the shoe 81. This shoe 81 carries an index tooth 84 for coaction with a notched index plate 85 of the same type as the plate 78,

except that it is concave to conform to the bar 80 instead of convex.

The disk 28 has secured thereto a vertically disposed bracket sleeve 86. Extending across the upper end of this sleeve is a horizontal slotted guide bar 87. The slot 88 of this bar extends across a slot 89 which is formed in and longitudinally of the table bar 39 at one side of the transverse center thereof, as shown in Fig. 3. The slotted bar 87 carries and has securely fixed thereto the downwardly extending pin 90 which passes through the sleeve 86, as shown in Fig. 1.

The rack bar 46 has secured thereto and extending downwardly therefrom a pin 91 which passes through the slot 89 in the table bar and engages in the slot of the slotted bar 87.

The plates 21 and 38 may be secured against relative movement by a suitable clamp such as is shown in Fig. 1 and indicated by the numeral 92.

Teeth formed or designed upon the present machine may be made in blocks varying in measurement from 28 to 36 m. m. in mesio distal length. The angle of the cusps may vary from 10 to 35° and the angle of the block with the median line may vary from 10 to 20° and the curvatures may differ anywhere from 3 to 6". All of these variables due to the size of the teeth are taken care of in the several adjustments which may be made in the grinding machine or a change in the guides and guide blocks or shoes. It might be said that a 30 or 32 m. m. block with the teeth ground by using guide plates 51 and 53 having a 4" radius edge and guide plates 52 and 54 having a 5" radius edge would be called medium and could be used in a great majority of cases and also in the majority of cases the blocks when set in the patient's mouth would make approximately a 17½° angle with the median line, although this angle might vary with the size of tooth and size of the mouth.

The guide frame 65, or the frame 66 when it is mounted upon the unit 57, is adjustable to any angle for obtaining the approximate angle between a block of teeth, composed of the bicuspids and molars and the median line. This adjustment is obtained by the use of the scale 93 formed on the face of the hand-piece 57 at the forward edge of the opening 94 which is concentric with the center of the frame 65 or the screw 69. The bar portion 67 of the frame 65 has an index point 95 thereon which is viewable through the aperture 94 for use in association with the scale. This adjustment is for right and left sides of the stud and nut 67-71 hold the guide frame in position on the offset portion 58 of the hand-piece or hand unit. The guide pins 64 engaging the edges of the vertical guide plates 51-53 keep the work centered with respect to the grinding wheel and impart a slight curved movement which is incorporated in the curvature of the cusps, when the hand unit is moved up and down while maintaining the blocks 62 in sliding engagement with the guide plates 51. As will be readily seen upon reference to Figs. 1 and 2, the guide plates are used in pairs set 180° apart or directly opposite and the guide plates 51 and 53 have the same 4" radius while the other guide plates 52 and 54 have a 5" radius and are set on the shafts at 90° from the 4" radii guides 52-54.

The frame of the hand unit has been shown in position with the blocks 62 in contact with the vertical guide plates 51. The guide pins 64 are shown engaged against the inner guide plates 53.

52—54. The modeling block 74 is held in the removable support or holder 73 which is detachably slidably connected with the shoe 72. This shoe 72 can be moved and indexed, by means of the tooth 71 and plate 78, along the curved forward bar 68 of the frame 65. This bar or convex portion 68 of the frame has a radius smaller than 5" to compensate for the distance from the wheel. In the case of the concave bar 80 of the frame 66, which is used for forming the lower teeth, the radius of the bar 80 is greater by the same distance.

The illustrations of the machine show the latter in what might be termed the neutral position in which the table 39 is perpendicular to the central plane of the grinding wheel 9 and it is from this position that the necessary adjustments are made for beginning the grinding of a block of teeth. Starting with the machine table in this position, a straight edge is placed across the guides 51 and the central point between the guides is marked thereon and the lower screw 32 is then employed for bringing this center into coincidence with the plane of the center of the grinding wheel. The wheel or stone is then backed away from the table by operating the lever 11 and the carriage or table is then rotated to an angle of approximately 25° with respect to the plane of the wheel, this angle being obtained by the use of the scale 34 and the marker 35. The screw 42 is then operated to move the carriage or table 39 on the block 36 away from the stone or wheel and at a 25° angle to such a point found by trial that when the stone is advanced, the edge will hit the center marked on the straight edge. While these adjustments are being made, the pin 91 which communicates motion to the rack 46 will be removed and is not put back into position until the table 39 is at the 25° position referred to and the above described adjustments have been made and the member 87 is then adjusted with reference to the pin in such a manner that the correct position of the guides 51 will be maintained through the rack and pinions 45 and 46 which govern the rotation of the standards 44. This adjustment of the member 87 will then be such that the members 44 will be rotated through 180° when the table 39 is rotated to 25° on the opposite side of the center of the grinding wheel. This action changes the position of all guides and brings guides 53 into operating position in place of the guides 51 or vice versa, and when the adjustments are properly made, the opposite edge of the wheel will hit the central point located by the straight edge when the table is rotated as described. After making these preliminary adjustments, a modeling block such, for example, as the block 74, is secured in place in a holder 73 by the use of a suitable modeling compound and the holder is then placed in the shoe 72. The frame 65 will be set to the desired operating angle, such, for example, as the 17½° angle described and then if the left side of the table 39 has been swung toward the grinding wheel to the operating position of 25° with the plane of the wheel, and an up and down movement be given to the hand-piece with the blocks 62 in contact with the guides 51 and with the pins 64 in contact with the guides 52 and 54, such an arcuate movement will be described by the modeling block with reference to the revolving grinding wheel that an upper distal convex surface of a cusp will be formed. The shoe will be given the necessary adjustments along the bar 68 as

designed by the index plate 78 until all of the parallel cuts have been made in the block.

When the carriage or table 39 is then rotated with the right hand side thereof towards the wheel and to a 25° angle opposite from its first position, the standards 44 will be rotated through 180° through the mechanical connection of the rack and pinions between them and the table, thus bringing the guides 53 into working position for engagement by the blocks 62. The shoes or blocks 62 will then be turned over to present their concave surfaces to the convex guides 53 and with the guide pins 64 in position against guides 54 and 52 which have also been changed when the shafts 44 rotated, the up and down movement of the hand piece in the same manner as previously described, will import such an arcuate movement to the modeling block with respect to the grinding wheel that an upper mesial concave surface of a tooth cusp will be formed. These arcuate cusp surfaces have one definite curve produced by the guides 51 and 53 which have a 4" radius as previously stated.

The pins 64 have been described as operating to keep the work centered and impart a slight curved movement to the hand unit which gives a curvature to the cusps. By forming the threaded studs 63 of these pins eccentrically as previously described, provision is made for a retruded bite, which the normal jaw with the natural teeth in place makes. Provision for this retruded movement of the lower jaw must be made in the design of the artificial teeth by giving a slight clearance between the lower distal half of each cusp and the upper mesial half of each upper cusp. By "retruded bite" is meant a clearance between the upper and lower cusps of the teeth which permits the jaw to move distally a definite amount, which may approximate .02". Because of the angular operating position of the guides 44 with respect to the stone, the necessary adjustment cannot be made by the movement of the block 25 on the body 23, therefore, the guide pins 64 are made eccentric and by rotating the pin 64 through 180°, the hand piece is set over one-half of the desired clearance for the retruded movement and clearance, the other half of this clearance being ground from the opposing block of teeth.

After forming the cusps in the manner described, the block is removed and is hand-carved for the esthetics of the case, but the main outlines of the ground surfaces are preserved. A mold is then made from this model and the porcelain is cast or shaped in the mold. This molded or shaped porcelain body is then fired and since the firing operation causes the porcelain to shrink, this shrinkage is taken care of by using two sets of index plates, one for the model and one for the finished porcelain. After annealing, the porcelain block of teeth is accurately located in the holder 73 by a jig and is lightly ground to conform to the size called for by the index plate. A set of index plates consists of an upper and lower, one each for the pattern and one each for finish. With accurate index plates and a properly constructed machine, all teeth of the same design and measurements will articulate and fit perfectly. The index plates are made so that the upper and lower cusps interlock. The formation of the cusps are the same in upper and lower, right or left, and at the same predetermined angle with the occlusal plane in each particular design. The angle of the block with the median line is the same, but the occlusal curva-

ture of the upper is convex and of the lower is concave.

What is claimed is:—

1. A grinding machine of the character described, comprising a rotatable grinding disk, a carrier for a body to be ground against the edge of said disk, means forming a pair of vertically spaced guides adjacent the disk and disposed at opposite sides of the vertical plane of the same, and means forming a part of said carrier for sliding contact with said guides, said guides being so constructed and arranged that the carrier when moved vertically along the same will move the said body in a vertical arcuate path against the edge of said disk and in a curved path in a plane perpendicular to the arcuate path.
2. A grinding machine for modeling cusps for artificial posterior teeth, comprising a rotary grinding disk, a pair of standards disposed upon opposite sides of the vertical plane of said disk, a vertical guide plate carried by each standard and having a longitudinally curved edge form, a manually actuated unit formed to extend across and connect said standards and having portions for slidable engagement with the edges of said guide plates, means carried by said unit for supporting a body in position for contact with the edge of said disk, and said plates having vertically extending edges curved to effect the movement of said body in an arcuate path with respect to said disk edge when the unit is moved vertically in contact with the plates.
3. A grinding machine for modeling cusps for artificial posterior teeth, comprising a rotary grinding disk, a pair of standards disposed upon opposite sides of the vertical plane of said disk, a vertical guide plate carried by each standard and having a longitudinally curved edge form, a manually actuated unit formed to extend across and connect said standards and having portions for slidable engagement with the edges of said guide plates, means carried by said unit for supporting a body in position for contact with the edge of said disk, said plates having vertically extending edges curved to effect the movement of said body in an arcuate path with respect to said disk edge when the unit is moved vertically in contact with the plates, and means supporting the standards facilitating disposing the same in a common vertical plane extending across the edge of and obliquely of the plane of said disk.
4. A grinding machine for modeling cusps for artificial posterior teeth, comprising a rotary grinding disk, a table pivotally supported adjacent the edge of said disk with its pivotal center disposed vertically and in the vertical plane of the disk, a pair of standards carried by and rotatable on the table and disposed upon opposite sides of said center, guide elements carried by and extending longitudinally of said standards above the table, said guide elements having longitudinally curved outwardly directed edges, a frame member adapted to extend across said standards, means carried by said frame for sliding contact with the curved edges of certain of the plates carried by said standards whereby said frame when moved vertically will be guided in a vertical arcuate path, and means carried by said frame for supporting a modeling block in position for engagement with the edge of said grinding disk.
5. A grinding machine for modeling cusps for artificial posterior teeth, comprising a rotary grinding disk, a table pivotally supported adjacent the edge of said disk with its pivotal center disposed vertically and in the vertical plane of the
- disk, a pair of standards carried by and rotatable on the table and disposed upon opposite sides of said center, guide elements carried by and extending longitudinally of said standards above the table, said guide elements having longitudinally curved outwardly directed edges, a frame member adapted to extend across said standards, means carried by said frame for sliding contact with the curved edges of certain of the plates carried by said standards whereby said frame when moved vertically will be guided in a vertical arcuate path, means carried by said frame for supporting a modeling block in position for engagement with the edge of said grinding disk, and means carried by said frame and engaging the curved edges of certain other ones of the plates of said standards for imparting an arcuate movement to the frame as the same is moved vertically opposite to the first-mentioned arcuate movement.
6. A grinding machine for modeling cusps for artificial posterior teeth, comprising a rotary grinding disk, a table pivotally supported adjacent the edge of said disk with its pivotal center disposed vertically and in the vertical plane of the disk, a pair of standards carried by and rotatable on the table and disposed upon opposite sides of said center, guide elements carried by and extending longitudinally of said standards above the table, said guide elements having longitudinally curved outwardly directed edges, a frame member adapted to extend across said standards, means carried by said frame for sliding contact with the curved edges of certain of the plates carried by said standards whereby said frame when moved vertically will be guided in a vertical arcuate path, means carried by said frame for supporting a modeling block in position for engagement with the edge of said grinding disk, and means facilitating the oscillation of said last means on an axis extending transversely of the frame in the plane of said disk whereby the said modeling body may be oscillated with respect to the edge of the disk.
7. A grinding machine for modeling cusps for artificial posterior teeth, comprising a rotary grinding disk disposed in a vertical plane, a table mounted for oscillation on a vertical pivot disposed in the said plane of the disk, means for shifting said table horizontally toward or away from the disk, a pair of standards rotatably supported on the table in spaced relation and at opposite sides of the plane of the disk, a plurality of guide plates carried by and extending longitudinally of each standard above the table, the disks of each standard being divided into two groups in which one group has longitudinal concave outer edges and the other group has longitudinal convex outer edges, means whereby oscillation of the table to either of two angular positions with respect to the plane of said disk will dispose plates of corresponding edge formation in parallel relation, a frame adapted to extend between the standards, means carried by the frame for sliding contact with the curved edges of the said parallel plates, said frame being designed for vertical movement against said parallel plates whereby the edge formation of the plates will impart vertical arcuate movement to the frame, and means for securing a modeling body to the frame in position to be contacted by the edge of said disk when the frame is given said vertical movement.
8. A grinding machine for modeling cusps for artificial posterior teeth, comprising a rotary grinding disk disposed in a vertical plane, a

table mounted for oscillation on a vertical pivot disposed in the said plane of the disk, means for shifting said table horizontally toward or away from the disk, a pair of standards rotatably vertically supported on the table in spaced relation and at opposite sides of the plane of the disk, a plurality of guide plates carried by and extending longitudinally of each standard above the table, the disks of each standard being divided into two groups in which one group has longitudinal concave outer edges and the other group has longitudinal convex outer edges, means whereby oscillation of the table to either of two angular positions with respect to the plane of said disk will dispose plates of corresponding edge formation in parallel relation, a frame adapted to extend between the standards, means carried by the frame for sliding contact with the curved edges of the said parallel plates, said frame being designed for vertical movement against said parallel plates whereby the edge formation of the plates will impart vertical arcuate movement to the frame, means for securing a modeling body to the frame in position to be contacted by the edge of said disk when the frame is given said vertical movement, and means whereby said last-mentioned means may be oscillated on a horizontal axis disposed in the plane of the disk to arrange the modeling body at a desired angle with respect to the edge of the disk.

9. A grinding machine for modeling cusps for artificial posterior teeth, comprising a rotary grinding disk disposed in a vertical plane, a table arranged horizontally transversely of said disk adjacent the edge thereof, supporting means for said table for oscillating the same on a vertical axis disposed in the plane of the disk, means for shifting said table horizontally toward or away from the disk, means for shifting the table horizontally transversely of the disk, a frame unit, means carried by the frame unit for supporting a modeling body thereon, for engagement with the edge of said disk, and coacting means between the table and said frame at opposite sides of the plane of said disk for effecting the simultaneous movement of the frame along two separate arcuate paths as the frame is manually moved vertically with the modeling body carried thereby in contact with the edge of the disk.

10. A grinding machine for modeling cusps for artificial posterior teeth, comprising a rotary grinding disk disposed in a vertical plane, a table arranged horizontally transversely of said disk adjacent the edge thereof, supporting means for said table for oscillating the same on a vertical axis disposed in the plane of the disk, means for shifting said table horizontally toward or away from the disk, means for shifting the table horizontally transversely of the disk, a frame unit, means carried by the frame unit for supporting a modeling body thereon, for engagement with the edge of said disk, coacting means between the table and said frame at opposite sides of the plane of said disk for effecting the simultaneous movement of the frame along two separate arcuate paths as the frame is manually moved vertically with the modeling body carried thereby in contact with the edge of the disk, means whereby the said modeling body may be adjusted with respect to the edge of the disk through oscillation on an axis disposed horizontally in the plane of the disk, and means for shifting the modeling body with respect to the frame in a path transversely of said oscillation axis.

11. A grinding machine for modeling cusps

for artificial posterior teeth, comprising a rotary disk disposed in a vertical plane, a table extending transversely of the edge of said disk and mounted for oscillation on a vertical axis lying in said plane, means for shifting said table in a horizontal path toward and away from the edge of the disk, means for shifting the table in a horizontal plane along a path perpendicular to said plane, a pair of standards rotatably supported vertically on the table upon opposite sides of said plane, a plurality of plates carried by each standard above the table and extending longitudinally of the standard, the disks of each standard being divided into one group having longitudinal concave outer edges and a second group having longitudinal convex outer edges, a gear carried by each standard, a rack connecting said gears, means for effecting longitudinal reciprocation of said rack upon oscillation of the table on the said vertical pivot therefor, a frame constructed to extend across and between said standards through the plane of the disk, bodies carried by said frame and each adapted to slidably contact an edge of a plate of a standard, pin members carried by the frame to extend transversely with respect to the standards and each designed for sliding contact with an edge of a plate of a standard, and means carried by the frame for supporting a body in position for contact with said disk edge when said first bodies are contacting their respective standard plates, said bodies, pins and plates coacting to impart arcuate movement to the frame and modeling body along two paths when the frame is moved vertically.

12. A grinding machine for modeling cusps for artificial posterior teeth, comprising a rotary grinding disk disposed in a vertical plane, a table mounted for oscillation on a vertical pivot in said plane, a pair of standards supported vertically upon the table upon opposite sides of said plane, a series of guides extending longitudinally of and carried by each standard above the table, each series being divided into a group having longitudinally convex edges and a group having longitudinally concave edges, a frame adapted to extend through said plane and across said standards, a guide contacting body at each end of the frame, a guide contacting pin at each end of the frame and extending transversely thereof to position across a guide, said pins being spaced to position between the standards, a modeling body support secured to said frame to position adjacent the edge of said disk when said pins and bodies are in contact with their respective guides, said modeling body supporting means being joined to the frame for oscillation on a horizontal axis lying in the plane of the disk, and means for moving the modeling body supporting means along an arcuate path extending across said plane, the guides engaged by said bodies being of duplicate character and the guides engaged by said pins being of opposite character whereby vertical movement of the frame will impart thereto vertical arcuate movement along two paths.

13. A grinding machine for modeling cusps for artificial posterior teeth, comprising a rotary grinding disk disposed in a vertical plane, a table mounted for oscillation on a vertical pivot in said plane, a pair of standards supported vertically upon the table upon opposite sides of said plane, a series of guides extending longitudinally of and carried by each standard above the table, each series being divided into a group having longitudinally convex edges and a group having

longitudinally concave edges, a frame adapted to extend through said plane and across said standards, a guide contacting body at each end of the frame, a guide contacting pin at each end 5 of the frame and extending transversely thereof to position across a guide, said pins being spaced to position between the standards, a modeling body support secured to said frame to position adjacent the edge of said disk when said pins 10 and bodies are in contact with their respective guides, said modeling body supporting means being joined to the frame for oscillation on a horizontal axis lying in the plane of the disk, means for moving the modeling body supporting means 15 along an arcuate path extending across said plane, the guides engaged by said bodies being of duplicate character and the guides engaged by said pins being of opposite character whereby vertical movement of the frame will impart there- 20 to vertical arcuate movement along two paths, said standards being mounted for oscillation, and means for effecting the simultaneous oscillation of the standards to change the characters of the guides engaged by said bodies and pins upon oscil- 25 lation of the table on its pivotal axis.

14. A grinding machine for modeling cusps for artificial posterior teeth, comprising a grinding disk, a table oscillatably mounted on a pivotal axis arranged in the plane of the disk, means 30 for shifting said table along two perpendicularly related horizontal paths, a frame, means for supporting a modeling body on the frame, the frame being adapted to be manually held in position for 35 contacting the periphery of the disk with the modeling body, means for shifting the modeling

body supporting means along an arcuate path extending across the plane of said disk, indexing means for noting the position of the modeling body supporting means in said arcuate path with respect to the disk, and guiding and centering means operatively coupling the frame with the table which is so constructed and arranged that upon manual movement of the frame vertically the frame will be given a movement along two opposite arcuate paths. 5

15. A grinding machine for modeling cusps for artificial posterior teeth, comprising a grinding disk, a table oscillatably mounted on a pivotal axis arranged in the plane of the disk, means for shifting said table along two perpendicularly related horizontal paths, a frame, means for supporting a modeling body on the frame, the frame being adapted to be manually held in position for contacting the periphery of the disk with the modeling body, means for shifting the modeling body supporting means along an arcuate path extending across the plane of said disk, indexing means for noting the position of the modeling body supporting means in said arcuate path with respect to the disk, guiding and centering means operatively coupling the frame with the table which is so constructed and arranged that upon manual movement of the frame vertically the frame will be given a movement along two opposite arcuate paths. 10
